CLAIM

The ornamental design for a rocking toothbrush sanitizer, as shown and described.

DESCRIPTION

FIG. 1 is a front perspective view of a rocking toothbrush sanitizer of the present invention;

FIG. 2 is another perspective thereof;

FIG. 3 is a reduced front elevation view thereof showing without the environment;

FIG. 4 is a reduced rear elevation view thereof showing without the environment;

FIG. 5 is a reduced left side elevation view thereof showing without the environment;

FIG. 6 is a reduced right side elevation view thereof showing without the environment;

FIG. 7 is a reduced top plan view thereof showing without the environment; and,

FIG. 8 is a reduced bottom plan view thereof showing without the environment.

The broken line showing of a toothbrush in FIGS. 1 and 2 represents the environmental subject matter and forms no part of the claimed design.
